CENTRIFUGAL CASTING APPARATUS AND THE
METHOD OF MAKING THE SAMEPaul F. Haughton, Ringgold, Ga., assignor to Combustion
Engineering, Inc., Windsor, Conn., a corporation of
DelawareFiled Nov. 2, 1961, Ser. No. 149,621
4 Claims. (Cl. 22—65)

This invention relates to apparatus for the centrifugal casting of metal, and the method of making the same.

One method used today for making metal tubing or pipes is to centrifugally cast hollow cylindrical castings by pouring a molten metal into a mold rotating at high speeds. The inner and outer surfaces of the so-formed castings are then machined to form smooth, flawless cylindrical surfaces. These machined pieces or hollows can thereafter be passed through a reducing machine which will reduce the diameter of such pieces, thereby extending the length, if desired.

The centrifugal casting apparatus presently in use today will not always produce perfect castings. A large percentage of such castings contain flaws such as porous areas, laps, or cracks which require considerable grinding, machining, and sometimes the necessity of cutting off the end portions of such castings. Such flaws or imperfections are caused due to critical factors such as pouring time, temperatures, and the r.p.m. of the rotating mold.

It is an object of my invention to provide a centrifugal casting apparatus and method of making the same which will produce castings of a superior quality containing less flaws therein than heretofore possible by presently known centrifugal casting apparatus.

It is a further object of my invention to provide a new and improved mold means and the method of making the same whereby configurations or irregularities are formed on the inner surface of the mold or the mold lining, the effect of which is to pump the molten metal into a circular orbit rather than to allow it to freely run down the mold, so that the molten metal moves along the length of the mold in a solid front.

Other objects and advantages will become apparent from the following description taken in conjunction with the accompanying drawings wherein:

FIGURE 1 is a side view of a centrifugal casting apparatus utilizing my invention;

FIGURE 2 is a plan view taken on line 2—2 of FIGURE 1;

FIGURE 3 is an end view taken on line 3—3 of FIGURE 1;

FIGURE 4 is a cross section of the mold used in FIGURE 1;

FIGURE 5 is an enlarged partial cross section taken on line 5—5 of FIGURE 4;

FIGURE 6 shows a partial casting made in accordance with my invention;

FIGURE 7 shows a partial casting made by conventional casting apparatus.

Looking now to FIGURES 1—3 of the drawings, mold means are shown comprising a mold 10 and a mold lining 60, to be used for the centrifugal casting of the hollow cylindrical metallic castings. This mold is rotated during the casting process by means of a motor 12, which rotates or drives pairs of rollers or bearing 20 and 22 secured on shaft 18 by means of drum 14 and belt 16. Members 24 and 26 which are fixed or secured in a suitable manner support the rotating shaft 18. The other side of mold 10 is supported by pairs of rollers or bearings 28 and 30 which are rotatable along with the shaft 32. Fixed members 34 and 36 support the shaft 32.

The left and right ends of mold 10 contain flanges 38 and 40 respectively, and end cores 42 and 44 containing

2

central openings are removably secured, for example by bolts, to flanges 38 and 40 during the casting process to prevent molten metal from being spun out of the ends of mold 10.

Molten metal which is melted in an electric induction furnace (not shown) is transferred into pouring ladle 46, and from there it is poured into boot 48 and flows from boot 48 into the hollow interior 62 of mold 10 by means of spout 50. Gas burners 52 are used to preheat the mold to a temperature of from 400—500° F. during the casting process. As illustrated in FIGURES 1 and 2, a thin layer of a suitable lining material 60 is formed on the inner surface of mold 10 to prevent the molten metal being cast from coming in contact with and becoming fused to the interior of mold 10. This lining material must completely cover the inner surface of mold 10, for if the molten metal were to come in contact with mold 10 even in a few small spots, the fusion formed thereby would be sufficient to prevent the later removal of the casting from the mold.

FIGURE 4 illustrates one form of the configurations or irregularities that can be formed on the inner surface of the mold or the mold lining which allows more perfect castings to be consistently made in accordance with my invention. As illustrated in FIGURE 4 a plurality of spiral grooves 70 are formed, which grooves will pump the molten metal into a circular orbit when the mold is rotated, thus making the molten metal move along the length of the mold in a solid front. These grooves are spiraled from the right end of the mold to the left end so that they tend to slow up, or retard, the flow of molten metal which moves from left to right down the length of the mold when it is rotated counterclockwise as shown by the arrows in FIGURE 4.

The preferred method of forming these grooves 70 will now be described. A spray nozzle is moved through the mold while the mold is rotating, to spray a thin coating of a suitable lining material of even thickness on the inner surface of the mold 10. Next a member containing a plurality of prongs or fingers is pushed longitudinally through the mold while it is rotating very slowly. The prongs or fingers are in engagement with the inner surface of the mold, and thus will remove a portion of the lining, forming the spiral grooves 70 as illustrated. The prongs will cut grooves which extend through the entire depth of the first coating of lining material. Since the lining material is considerably softer than the metal of the permanent mold 10, the forming of the grooves is easily accomplished. After this step the spray nozzle is again passed through the mold, spraying on a second coating of lining material so that the entire inner surface of the mold has a lining thereon. The depth of the lining material in the spiral groove will thus only be half that covering the rest of the inner surface of the mold, as seen in FIG. 5. After this has been done end cores 42 and 44 containing central openings are inserted and the apparatus is ready for a casting to be poured.

It is not necessary to form the grooves such as illustrated in FIGURES 4 and 5 on the lining material itself. Instead it would be possible to form the grooves in the metal of the mold itself, and thereafter spray on the lining material. In the case of the spiral configuration formed in the mold itself, it would be necessary to have the mold slightly tapered from one end to the other in order to permit the casting to be withdrawn therefrom. The space between the grooves, the angle of the spiral, and the width of the grooves is not critical, and any dimensions can be used.

Obviously, by decreasing the r.p.m. of the mold, or increasing the speed at which the pronged member is moved through the mold during the grooving operation, the axial distance between each coil can be increased.

An example of a suitable distance between coils of the spiral would be one inch. This could be formed by rotating the mold at twenty r.p.m. while moving the pronged member therethrough at a speed of ten feet per minute, if the pronged member contained six equally spaced prongs or fingers, all of which engaged the inner surface of the mold.

The optimum method of forming the configurations or irregularities from tests run was found to be as follows: (1) first a coating of lining material approximately .02 to .03 inch thick was sprayed onto the inner surface of the mold; (2) a plurality of spiral grooves were scratched into the lining material by pushing a member containing a plurality of fingers thereon through the mold while it was rotating very slowly; and (3) spraying in .02 to .03 inch of a second coating of the lining material. The thickness of the lining is not overly critical, as long as it is sufficient to prevent fusing of the molten metal with the mold. Also, the lining could be formed in a manner other than by spraying it on. Any suitable lining material can be used. A semi-permanent lining, such as a rammed refractory lining, can be used if desired. In the above described operation a mixture of diatomaceous earth containing a small percentage of bentonite clay and sodium silicate as a binder was used. A new lining of this material is formed after each casting.

FIGURE 6 illustrates the manner in which the forward portion of the advancing molten metal moves along the length of the mold in a solid front when utilizing a grooved lining. FIGURE 7 illustrates how the forward portion of the advancing molten metal moves in a casting made by conventional casting apparatus having a smooth lining therein. A small charge of molten metal insufficient to form a whole or complete casting was poured under like conditions into a rotating mold to form each of these pieces illustrated in FIGURES 6 and 7, so that the advancing portion of the molten metal froze or solidified in the shapes shown. As can be seen in FIGURE 6 where a spiral groove was formed in the lining, the molten metal moved along the mold in a solid front. As shown in FIGURE 7 the molten metal poured in a mold containing a smooth lining moved along the mold in the form of a long, lazy spiral. Not shown in the figure but quite important is the cross section of the two pieces. The piece in FIGURE 6 will have a uniform wall thickness on the advancing edge while that in FIGURE 7 will have a tapered cross section varying from $\frac{1}{64}$ " to $\frac{1}{4}$ ".

The use of the spiral grooves results in many advantages. With standard pouring techniques utilizing a smooth mold, excessive laps, cracks, and porous areas are frequently found in the castings. The results of a test comparing castings made utilizing a standard smooth lining as against utilizing a spiral grooved lining showed three times as many castings required repair after machining when using a smooth lining as when using a grooved lining, all other factors constant.

When utilizing a standard smooth lining, it is necessary to rotate the mold below a predetermined maximum r.p.m. in order to prevent "hoop stress" cracking, which are longitudinal cracks in the castings which form when too high a r.p.m. is used. When using a smooth lining, "hoop stress" cracks usually start to appear when approximately 1300 r.p.m. is exceeded. When utilizing the grooved lining in accordance with my invention, it is possible to rotate the mold at 1650 r.p.m. or even higher without encountering any "hoop stress" cracking. One advantage of using a high r.p.m. is that it aids the molten metal in going into "orbit" sooner and prevents "raining," which is droplets of molten metal falling down into the central portion of the casting when the centrifugal force is not sufficiently high. Another advantage is that the casting is more free of inclusions. A further advantage of using a grooved lining is that the pouring time is not as critical when using the grooved lining, and less

flaws are formed when too fast or too slow a pour is made than is formed when using a smooth lining.

The optimum pouring time when utilizing my invention for a 460 pound casting poured into a mold a little over 10 feet long and $4\frac{1}{8}$ inches in diameter is 30 seconds. The casting formed has a wall thickness of approximately 1.125 inches. After the casting has cooled sufficiently in the mold, the end core 44 is removed, and the casting can be pulled out of the mold. The inner and outer surfaces of the casting are then machined to form perfectly smooth, flawless, cylindrical surfaces. Such machining will remove the small irregularities from the outer surface of the casting caused by the grooves in the mold means, either the mold or the mold lining.

It is possible to cast most any type of metal or alloy with my above described apparatus. Many types have been already cast, including ferritic steels such as T2, T3b, T9, T11, and T22; austenitic steels such as TP304, TP316 and TP347; Cu-Mo alloys; Inconel; and many others.

While I have shown and described the preferred embodiments of the invention it is to be understood that the invention is not limited thereto but may be otherwise variously embodied and practiced within the scope of the following claims.

What I claim is:

1. Apparatus to be used for centrifugal casting including a mold, a layer of lining material on the inside of said mold, said mold having a first, pouring end, and a second, nonpouring end, means for pouring molten material at the pouring end only, means for rotating said mold in one preselected direction, spiral groove means formed in the inner surface of said lining material, said spiral groove means extending in one direction only, from the pouring end toward the nonpouring end in a direction opposite to said preselected direction of rotation.

2. Apparatus to be used for centrifugal metal casting including a mold, said mold having a first, pouring end, and a second, nonpouring end, means for pouring molten metal at the pouring end only, means for rotating the mold in one preselected direction, lining means covering the inner surface of said mold for preventing the casting from becoming fused to the mold, and a spiral irregularity in the inner surface of said lining means for causing the molten metal being cast to be pumped into a circular orbit, so that it moves along the length of the mold in a solid front, said spiral irregularity extending in one direction only, from the pouring end toward the nonpouring end in a direction opposite to said preselected direction of rotation.

3. Apparatus to be used for centrifugal metal casting including a mold, said mold having a first, pouring end, and a second, nonpouring end, means for pouring molten metal at the pouring end only, means for rotating said mold in one preselected direction, lining means coating the inner surface of said mold for preventing the casting from becoming fused to the mold, a spiral groove formed on the inner surface of the lining means for causing the molten metal to be pumped into a circular orbit as the mold rotates, so that it moves along the length of the mold in a solid front, said spiral groove extending in one direction only, from the pouring end toward the nonpouring end in a direction opposite to said preselected direction of rotation.

4. Apparatus to be used for centrifugal metal casting including a substantially hollow cylindrical mold, said mold having a first pouring end and a second, nonpouring end, means for pouring molten metal at the pouring end only, means for rotating the mold in one preselected direction, lining means covering the inner surface of the mold for preventing the casting from becoming fused to the mold, and a spiral irregularity in the inner surface of said lining means for causing the molten metal being cast to be pumped into a circular orbit, so that it moves along the length of the mold in a solid front, said spiral irregu-

larity extending throughout substantially the entire length of the mold in one direction only, from the pouring end toward the nonpouring end in a direction opposite to said preselected direction of rotation.
